UNITED STATES PATENT OFFICE

EDMUND BERNARD DOWD, OF CHICAGO, ILLINOIS

MEANS FOR FORMING PLASTIC COLUMNS

Application filed July 31, 1926. Serial No. 126,144.

This invention relates to means for forming plastic material about a steel structure to provide a composite column, although certain features thereof may be employed with equal advantage for other purposes.

It contemplates more especially the provision of standard units of any suitable form which bear a relation to each other to facilitate the assembly thereof so as to produce with ease, a mold or lagging of any desirable size and design which may be readily dismantled and repeatedly used without impairing their utility.

Numerous types of molds have heretofore been proposed for use especially in forming reinforced concrete or other plastically formed columns, but these have not proven entirely satisfactory in that they must necessarily be specially constructed for each individual column which is not only laborious and expensive, but also renders them of little value after the column has set, it being necessary that they be partially or wholly destroyed in order to effect the removal thereof.

Further, the lagging must be properly centered about the particular beam or steel structure to be reinforced, and to accomplish this end novel means are provided which are detachably associated with the lagging so as to permit the removal of the latter without disturbing the former which may be retained within the plastic material to reinforce the structure.

One object of the present invention is to improve and simplify the construction of devices of the type mentioned.

Another object is to provide standard units which bear a relation to each other to facilitate repeated assembling and dismantling of the related units without impairing their utility.

A further object is to provide improved unitary means for spacing and reinforcing the lagging, thereby rendering the latter capable of withstanding appreciable stresses prevalent prior to the setting of the material contained therein.

A still further object is to provide reinforcing means capable of association and disassociation with the lagging so that the latter

may be removed independently of the reinforcing means.

Other objects and advantages will appear from the following description of an illustrated embodiment of the present invention. 55

In the drawings:

Figure 1 is a view in elevation showing a lagging embodying features of the present invention.

Figure 2 is a sectional view taken substantially along the line II—II of Figure 1. 60

Figure 3 is a fragmentary sectional view taken substantially along line III—III of Figure 1.

Figure 4 is a sectional view taken substantially along line IV—IV of Figure 1 after the plastic material has been placed therein. 65

Figure 5 is a fragmentary sectional view with parts omitted, taken substantially along the broken line V—V of Figure 2. 70

Figure 6 is a sectional view taken substantially along line VI—VI of Figure 3.

Figure 7 is a view taken substantially along line VII—VII of Figure 3.

Figure 8 is a sectional view taken substantially along line VIII—VIII of Figure 3. 75

Figure 9 is a sectional view taken substantially along line IX—IX of Figure 3.

Figure 10 is a sectional view of a modified column which is formed of plastic material having a central steel structure within a hollow interior. 80

The means selected for illustration is, in this instance, shown associated with an I-beam 10 of standard construction, which is disposed in a vertical position to constitute the skeleton of a column formed of plastic material to be hereinafter described. 85

In order to properly form the plastic material about the steel structure or core, in this instance the I-beam 10, suitable lagging must be provided to retain the plastic material in position prior to and during the setting thereof. In the present embodiment, the lagging comprises a tubular member 11 preferably constructed of sheet material, which is longitudinally sectioned to define, in this instance, corner sections 12 and intermediate sections 13 complementary to the corner or end sections to define a tubular member to serve 90

as a mold for the plastic material poured therein. It is to be noted that the sections 12 and 13 may be of any desirable height, and preferably are of varying height so that 5 standard units may be provided to enable the construction of a column of any desired length by placing the constituent units 14, 15, 16, et cetera, in superposed aligned axial relation to make possible the formation of a 10 column of any desired length. As shown, the corner sections 12 terminate in reinforced ends 17 which are beaded or otherwise bent upon itself to rigidify the longitudinal edges thereof so that the corner sections will not 15 be deformed or in any way defaced due to the rough usage and handling to which they are subjected.

To enable a ready and convenient positioning of the lagging 11 about the steel structure, in this instance the I-beam 10, spacing 20 strips 18 are provided, which when joined as will later appear herein from bands adapted to embrace the beam 10 and to detachably engage the lagging 11 which, in this instance, 25 constitutes the sections 12 and 13, so as to maintain the latter in spaced relation to the beam as well as to serve as a reinforcing means to assist the lagging in withstanding the stresses created thereon by the plastic 30 material placed therein.

In view of the fact that it may be necessary or at least highly desirable to use steel structures of various sizes as is quite common in building construction, it is advantageous to render the spacing strips 18 adjustable so as to adjustably embrace the I-beam 10 or other inner structures of varying sizes. The adjustable feature, in this instance, consists in providing overlapping adjacent 35 strips 18 which terminate in confronting hooks or loops 19 to receive therein a spacer 20, in this instance of sheet material preferably having inclined sides slidable within the loops 19 to cause strips 18 to embrace 40 the I-beam 10 by a wedging action created by the plate 20, as will be obvious from the showing in Figure 2. To retain the strips in their adjusted position, a clip 21 preferably of sheet material bent about itself, 45 is slidable on the overlapping ends of the strips 18 to resiliently embrace the latter, thereby maintaining them in the desired adjustment.

In the construction shown the strips 18 intersect each other at the corners of the I-beam 10 where they are provided with interfitting slits 22 to prevent relative movement therebetween. The projecting ends of the bands 18 terminate in and constitute angularly related members 23 which have a portion, in this instance an upper half or tongue 24, of their extremities projecting through appropriate slots 25 provided in the end sections 12. The extremities 24 are suitably apertured as 60 at 26, to receive a pin 27 which retains the

end section 12 against movement with respect to the spacing bands formed from the strips 18. The other half portions 28 of the projections 23 of the strips 18, are bent to define, in this instance, a triangle with the angular related projecting portions 23 so as to properly sustain the bands within the lagging with a view of reinforcing the latter which are subjected to excessive stresses during the 70 pouring of the plastic material therein.

The fact that the lagging may be of various designs and sizes makes it essential or at least highly desirable, to adjustably unite the bent ends 28 which are provided with complementary extensions, in this instance constituting U-shaped members 29 and 30 (Figure 6), which are slidable within each other and are retained in adjusted position by means of the pins 31 projecting through suitable apertures provided in the cooperating extensions 29 and 30. Thus it will be apparent that the spacing strips 18 may be readily adjusted to properly and rigidly center the lagging with respect to the steel structure, in this instance the I-beam 10, as well as be readily suspended within the lagging in detachable relation thereto so that the corner sections 12 may be removed independent of the spacing strip 18 by merely removing the pins 27 from their apertures 26 provided in the exteriorly projecting extremities 24 of the strips 18.

In order to render the lagging rigid so that it may withstand excessive stresses without being flexed, a plurality of spacing bands formed from strips 18 are provided at irregular spaced intervals along the length of the lagging, the spacing near the bottom thereof being much less and gradually becoming greater as will be apparent from the showing in Figure 1, to correspond with the stresses on the lagging which proportionally increase along the length thereof.

To retain the intermediate sections 13 in their related position with respect to the end sections 12, transverse cords, in this instance the angle bars 32, are disposed intermediate the portions 23 of the strips 18, they being provided with reduced extremities 33 which are adapted to project in suitable slots 34 provided in the portions 23 of the strips 18. A pin 35 is projected through a suitable aperture in the extremity 33, to maintain the bars 32 in a position adjacent the intermediate members 13. The bars 32 are detachably secured to the intermediate section 13 of the lagging 11 by means of the lugs 36 which are bent from sheet metal to define a triangular portion embracing the angle bar 32 at spaced intervals, the former being provided with confronting projections 37 which protrude through appropriate slots 38, in this instance three, provided at spaced intervals along the width as well as over the length of the sections 13. The lugs 36 are retained in position 120 125 130

by means of an exteriorly located pin 38' which projects through appropriate aligned apertures provided in the confronting projections 37.

5 With the arrangement of parts thus far described, it will be apparent that the sections 12 and 13 constituting lagging may be readily positioned relative to each other and maintained in their assembled relation by means 10 of the spacing strips 18 and the bars 32 which are so correlated that the lagging may be removed independent of the means retaining them in position, the latter remaining in the plastic material to reinforce the same. It is 15 to be noted that the projection 37 of the clips 36 may be either employed for securing any appropriate surface, such as brick or the like, to the column formed after the plastic material has been poured in the usual way, 20 or they may be removed by chiseling or otherwise shearing them off. In some instances it may be desirable to provide struts, in this instance, the crossed wires 39 which are secured to the spacing strips 18 and the bars 25 32 to reinforce the plastic material between the bands and the interior surface of the lagging.

Wherever hollow columns are desirable, the steel structure, in this instance the I-beam 30 10', may be provided with plates 40 (Figure 10) to enclose the I-beam so that the material poured between the lagging 11' and the plates 39 will present, after setting a reinforced column having a hollow interior. Otherwise the 35 construction and simulation of the component parts is similar to that discussed above.

It will be apparent from the above, that means constituting standard units, have been provided which may be assembled with ease 40 and repeatedly used to construct plastically prepared columns of any desirable shape or design without necessitating the provision of new lagging for each individual job.

I am aware that many changes may be 45 made, and numerous details of construction may be varied through a wide range without departing from the principles of this invention, and I therefore do not purpose limiting the patent granted hereon, otherwise than 50 necessitated by the prior art.

I claim as my invention:

1. Means for forming plastic material about an inner structure to provide a composite column, including sectional lagging 55 constituting a tubular sheet metal lagging, centering means spaced along the length of and within said lagging, said centering means projecting through said lagging, and securing means associated with the projecting portions 60 of said centering means to maintain said sections in assembled relation, said sections being removable independent of said centering means.

2. The combination with sectional lagging 65 defining a tubular member having spaced

slots in the walls thereof, of spacing strips within said member and projecting through said slots, and means for securing said strips to said sections, whereby the latter are maintained rigid.

3. Means for forming plastic material about an inner structure to provide a composite column, including sectional lagging, and spacer strips for centering said lagging about said structure, the intersecting extremities of said spacer strips being relatively adjustable, and means associated with said spacer strip extremities to maintain them in adjusted position.

4. Means for forming plastic material about an inner structure to provide a composite column, including sectional lagging of sheet material having spaced slots therein, and spacing strips within said lagging and projecting through said slots, said spacing strips defining an adjustable central portion to embrace said steel structure.

5. Means for forming plastic material about an inner structure to provide a composite column, including sectional lagging of sheet material having spaced slots therein, spacing strips within said lagging and projecting through said slots, said spacing strips defining an adjustable central portion to embrace said inner structure, and means for maintaining said strips in adjusted position.

6. Means for forming plastic material about an inner structure to provide a composite column, including sectional lagging of sheet material having spaced slots therein, spacing strips within said lagging and projecting through said slots, said spacing strips defining an adjustable central portion to embrace said inner structure, and means for maintaining said strips in adjusted position, 100 said means comprising confronting loops on said spacing strips, and a plate slidably associated with said loops.

7. Means for forming plastic material about an inner structure to provide a composite column, including sectional lagging of sheet material having spaced slots therein, spacing strips within said lagging and projecting through said slots, said spacing strips defining an adjustable central portion to embrace said inner structure, means for maintaining said strips in adjusted position, said means comprising confronting loops on said spacing strips, a plate slidably associated with said loops, and a clip associated with 115 said strips about said loops.

8. Means for forming plastic material about an inner structure to provide a composite column, including sectional lagging having slots in the walls thereof, spacing strips adjustably associated with said structure and engaging the slots in said lagging, said strips having apertured extremities, and pins projecting through said apertures.

9. Means for forming plastic material 120

about an inner structure to provide a composite column, including sectional lagging of sheet material, spacing bands adjustable to embrace said inner structure, said spacing bands having projections engageable with said lagging, and means detachably associated with said sections intermediate said projections to maintain said sections in assembled relation.

10. Means for forming plastic material about an inner structure to provide a composite column, including sectional lagging of sheet material, spacing bands adjustable to embrace said inner structure, said spacing bands having projections engageable with said lagging, and means detachably associated with said sections intermediate said projections to maintain said sections in assembled relation, said sections being removable 20 independent of said spacing bands and intermediate means.

11. Means for forming plastic material about an inner structure to provide a composite column, including lagging comprising 25 corner sections, intermediate sections complementary to said corner sections, spacing bands to embrace said inner structure, said spacing bands having projections engageable with said corner sections, angular members disposed intermediate said projections adjacent said intermediate sections, and clips for detachably securing said angular members to said adjacent sections.

12. Means for forming plastic material 35 about an inner structure to provide a composite column, including lagging comprising corner sections, intermediate sections complementary to said corner sections, spacing bands to embrace said inner structure, said spacing bands having projections engageable with said corner sections, angular members disposed intermediate said projections adjacent said intermediate sections, clips for detachably securing said angular members to 45 said adjacent sections, and struts tensioned between said bands and intermediate members.

13. Means for forming plastic material about an inner structure to provide a composite column, including lagging comprising 50 corner sections, intermediate sections complementary to said corner sections, spacing bands to embrace said inner structure, said spacing bands having projections engageable with said corner sections, angular members disposed intermediate said projections adjacent said intermediate sections, clips for detachably securing said angular members to said adjacent sections, said clips projecting 60 through the lagging, and securing means associated with said clips externally of said lagging.

14. Means for forming plastic material about an inner structure to provide a composite column, including sectional lagging,

means embracing said inner structure and engageable with said lagging to maintain the latter in spaced relation, and securing means associated with said means externally of said lagging.

15. Means for forming plastic material about a steel structure to provide a composite column, comprising sectional lagging, and adjustable spacing strips to embrace said steel structure, each of said strips having an angularly bent portion for abutting a corner section of said lagging and adjustably engaging with a corresponding portion of another of said strips.

16. Means for forming plastic material to provide a column, including lagging comprising corner sections and complementary intermediate sections, adjustably spacing strips detachably associated with said sections, each of said strips being split adjacent its outer ends to provide an upper and a lower portion, one of said portions extending through said lagging, the other of said portions being angularly bent to abut a corner section and to connect with a corresponding portion on another of said strips, and adjustable means for connecting said angular portions.

17. As an article of manufacture, an element interengageable with similar elements to form reinforcing means, said element comprising a strip split adjacent an end thereof, the portion of said strip on one side of said split projecting as a tongue, and the portion on the other side of said split being formed to define a channel member.

18. In combination, reinforcing means embracing a core, said means comprising a plurality of elements interengageable adjacent corresponding ends thereof, complementary pairs of said elements terminating in confronting hook-like portions permitting a wedge-like member to be placed therebetween to tighten said elements about said core, and lagging supported by said elements around said core.

19. In combination, reinforcing means for a plastic column and the like formed around a core, said means comprising a plurality of elements, each element being adjustably interengageable with a plurality of similar elements for forming bands to embrace said core, and lagging engageable and supported by said bands.

20. Means for forming plastic material about an inner core, including transversely sectional lagging, and adjustable spacing means for embracing said core and engageable with said lagging to support the same around said core in spaced relationship thereto.

21. Means for forming plastic material about an inner core, including side and corner sections of lagging, and means mountable within said lagging for centering the same

with respect to said core and for engaging said lagging to support the same around said core in spaced relationship thereto, said lagging being removable from said means without injury to said plastic material to leave a casting having a periphery of said plastic material.

22. Means for forming plastic material, including a plurality of like elements adjustable interengageable with each other to form a band, and sectional lagging removably engageable with and around said band to be supported thereby, said band remaining within said plastic material as reinforcing means when said lagging is removed.

In testimony whereof I have hereunto subscribed my name.

EDMUND B. DOWD.
